(57) **CLAIM**

The ornamental design for a plant protection device, as shown and described.

DESCRIPTION

FIG. 1.1 is an upper perspective view of a plant protection device, in accordance with an embodiment of the present invention;

FIG. 1.2 is a lower perspective view of the plant protection device of FIG. 1.1;

FIG. 1.3 is a front perspective view of the plant protection device of FIG. 1.1;

FIG. 1.4 is a top perspective view of the plant protection device of FIG. 1.1;

FIG. 1.5 is a bottom perspective view of the plant protection device of FIG. 1.1;

FIG. 1.6 is a top perspective view of the plant protection device of FIG. 1.1 in an unfolded configuration; and,

FIG. 1.7 is a bottom perspective view of the plant protection device of FIG. 1.1 in an unfolded configuration.
